(57) **CLAIM**

The ornamental design for a bottle with integrated grip portion, as shown and described.

DESCRIPTION

FIG. 1 is a top isometric view of a bottle with integrated grip portion;

FIG. 2 is a front elevation view of the bottle with integrated grip portion of FIG. 1;

A rear elevation view is identical to the view of FIG. 2;

FIG. 3 is a side elevation view of the bottle with integrated grip portion of FIG. 1;

A second side elevation view is identical to the view of FIG. 3; and,

FIG. 4 is a top plan view of the bottle with integrated grip portion of FIG. 1.

The broken lines in the drawings are for illustrative purposes only and do not form part of the claimed design.

The bottom of the bottle does not form part of the claimed design.
